BUILDING CONSTRUCTION

Emil A. Reither, Aitkin, Minn.

Application May 28, 1934, Serial No. 728,016

6 Claims. (Cl. 20—2)

This invention relates to building constructions and its objects are as follows:—

First, to provide a building constructed of uniformly turned logs, these being so interengaged along their lengths and at the corner joints as to entirely do away with the necessity of nails, bracing and similar supports.

Second, to provide a building which, because of the foregoing construction, can be disassembled simply by lifting off the succeeding layers of logs and then transported as easily as it was erected.

Third, to provide a log with a single groove longitudinally of its surface and double grooving longitudinally of its surface on the opposite side so as to produce a tongue at a place diametrically opposite to the single groove, said double grooving forming a channel to receive the crown of the next log.

Fourth, to build up the walls with the channels underneath each log so as to form a watercheck along the seams and so contribute to a weather-tight construction.

Fifth, to enable making a weathertight corner, as well as one of symmetrical and pleasing appearance, without having to apply any finishing material such as plaster, finishing strips, flashing, etc., either inside or outside.

Sixth, to provide an improved sill log of simple and weathertight construction.

Seventh, to use logs similar to the wall logs as partition logs.

In the drawing:—

Figure 1 is a vertical cross section of the lower portion of a building taken next to the foundation, certain partition logs and a fraction of a joist being shown in elevation.

Figure 2 is a side elevation of a portion of a building illustrating the crossing of the logs as in log-cabin construction.

Figure 3 is a plan view of the structure in Figure 2.

Figure 4 is a plan view of the next lowest layer of logs, the parts being shown as viewed on the line 4—4 of Figure 2.

Figure 5 is a detail side elevation of one of the false ends presently described.

Figure 6 is a detail section taken substantially on the line 6—6 of Figure 4.

The chief purpose of the invention is to enable the building of a cabin out of logs, but to make it watertight as the building progresses, the cabin having practically the same rustic effect of the well known log cabin but being minus the multifarious structural defects which compel chinking before it becomes habitable in bad weather. The

improved log cabin is capable of being erected as easily as it can be taken down, and in taking it down there is no likelihood of such harm befalling the logs and false ends as will prevent their being used again in a later building. These and other points are more clearly brought out in the following description.

In Figure 1 the foundation 1 may be made out of any suitable and available material. Generally it will consist of a concrete casting. This 10 is either rabbeted or socketed along the inturned upper margin as at 2 to receive the ends of joists 3 on which the floor (not shown) is eventually placed. Courses or layers of logs are laid on the foundation 1, beginning with the sill log 4.

This log (referring to one of them) has a little more than a quarter section cut out in its longitudinal direction as at 5 so as to produce a deep recess to receive the upper end of the foundation. In other words, the sill log 4 is laid upon the 20 foundation at the recess 5, the part 6 which remains of the log immediately adjacent to the recess comprising a flashing which prevents rain water from ordinarily working past the sill log toward the inside of the cabin.

Following the sill log course are superimposed courses or layers of logs which are herein called mortise and tenon logs because of their individual characteristics, these logs occurring in alternation. Figure 2 shows some of these superimposed 30 layers of logs. If the reader were to view the building from a standing position at the left side of Figure 1 and near the corner at his right he would see the layers in crossed relationship as in Figure 2.

The mortise logs are designated 7 and are so called because they have a hole or mortise 8 near each end (Figs. 3 and 4). The tenon logs 9 are so called because their ends 10 fits into the mortises 8. False ends 11 are applied to the outsides 40 of the mortise logs 7 so as to appear as continuations or extensions of the tenon logs 9, for which purposes the false ends have deep, semi-circular end cuts 12 (Fig. 5) to fit the outer contour of the mortise logs and are placed exactly 45 in line with the tenon logs. The false ends 11 thus look like the exposed ends 13 of the mortise logs 7 and give the building the characteristic crossed-log appearance.

Each mortise 8 is bored the diameter of the 50 respective mortise log 7. The diameter of the mortise 8 is substantially the same as the end 10 of the tenon log 9. All of the logs are turned to a uniform diameter. From this it will be understood that there is no bark on them. This 55

produces a particularly pleasing appearance on the interior, removing the necessity of applying any finishing material whatsoever.

All of the logs, including the false ends 11 have a single longitudinal groove in their upper surfaces. In the sill logs this groove is designated 14, in the mortise logs 7 it is designated 15, in the tenon logs 9 it is designated 16 and in the false ends 11 it is designated 17. Each groove 15 is continuous from end to end of the respective mortise log. The groove 17 is a continuation of the groove 16 because of the break between the false end 11 and the tenon log 9.

Each of the mortise and tenon logs and the 15 false end (this time excepting the sill log 4) has a double grooving running longitudinally of its surface on the nether side. The double grooving is designated 18 and it occurs on that side of the mortise and tenon logs and the false end 20 opposite to the foregoing single grooves. The double grooving produces a longitudinal tongue 19. This is diametrically opposite to the single groove in all characteristics. This tongue eventually becomes a key, so interengaging the logs 25 along their lengths and at the corner joints as to firmly hold the structure together without the use of nails or the like.

The double grooving forms a channel on the nether side of each log course. This channel 30 receives the crown 20 of the log course below and constitutes a water check because the surfaces of the channel slope downwardly and so make it difficult for the water to seep through. The interengaging grooves and tongues complete the 35 water check along the seams so that moisture will ordinarily not work through to the interior of the cabin. The foregoing arrangement produces an overlapping of the log courses, the extent being the lateral dimension of the double 40 or channel groove 18.

In finishing a log one of the first steps is to turn it down to the diameter of the smallest end. All 45 logs of the same general size will be turned to the same diameter. It has been found practicable to turn them down to as little as 3 $\frac{1}{8}$ '. There is not much more waste than the outside bark.

Next comes the grooving. The single groove at the top and the double grooving at the bottom is carried out in the longitudinal direction. One 50 comes opposite to the other so that when the walls are built up they will stand erect. The mortises 8 are bored into the mortise logs 7 a set distance from the ends at the mill. This leaves practically nothing more to be done at the site of the building 55 than to carry out the process of erection.

After having laid the sill course 4 which is built in mortise and tenon form, a regular mortise and tenon course comes next. This and all subsequent 60 courses are identical as far as mortise and tenon logs are concerned. Presuming the cabin to be square there will be a pair of mortise logs on two of the confronting sides and a pair of tenon logs on the two remaining confronting sides. The ends of the tenon logs fit into the mortises as 65 will be understood.

The next course will also be a mortise and tenon course but the pair of mortise logs will go on top of the tenon logs beneath, and the companion tenon logs will go on top of the mortise logs beneath. So in reading from bottom to top the 70 mortise and tenon logs will be found to alternate, and according to the same principle mortise and tenon logs will be found to alternate in reading around any given course.

As the log courses are built upon each other the

tongues and grooves will be interengaged. The tongues form keys which prevent pushing the walls outwardly. The false ends 11 may be put in place as the building progresses, but not necessarily so. They may be driven in later like plugs from the outside between the exposed ends 13 until the deep cuts 12 are stopped by the contours of the mortise logs. The interengaging tongues and grooves will hold the false ends in place.

The tongues 19 are cut out at 21 in two places, 10 only one place being shown (Fig. 6). This cut-out is usually made with a chisel on the job, and it occurs at the place 22 (Fig. 6) where the mortise logs 7 jut out over the cross mortise logs in the 15 course beneath. It will be understood from Figure 6 that the place 22 is the continuation of the outer contour of the mortise log of a given course, and since the mortise log of the course next highest crosses said mortise log something must be done at the place 22. Rather than to groove 20 said place in order to make room for the tongue 19, which of course would be feasible, it is preferred to cut the tongue at 21.

A further provision is that of a partition wall. The logs of that wall, designated 23 in Figure 1 25 for the purpose of distinction are set into mortises 24 at their remote ends, these mortises occurring on the insides of all of the logs in vertical series on those sides of the cabin which the partition is intended to abut. These partition logs will be 30 set into the mortises 24 as the construction progresses, other provisions being made for a door should a door be desired. The contacting crown and nether parts of the partition logs have a 35 groove and tongue construction (although not specifically illustrated) identical with that in the cabin walls.

In this description no provision is included for 40 doors and windows in the outer walls, that is to say, the superimposed layers of logs arranged in the form of an enclosure. But in practice there will be a door and window openings, and these will simply be framed according to the known custom.

I claim:—

1. A building construction comprising at least 45 two layers of logs, one superimposed on the other in the form of an enclosure, confronting pairs of logs in each layer having mortises to receive the tenon ends of the remaining logs of the respective layer thereby to make corner joints, the logs of one layer having grooves communicating and crossing at the corners, the logs of the other layer having tongues interengaging with the grooves and forming keys especially at the corner joints. 55

2. A building construction comprising superimposed layers of logs arranged in the form of an enclosure, one opposing pair of logs in each layer having mortises containing the tenon ends of the other pair of logs in the same layer, the 60 mortise and tenon logs alternating in the vertical direction, the ends of the mortise logs extending beyond the tenon logs, false ends projecting from the sides of the mortise logs in continuation of the tenon logs to produce a 65 crossed-log appearance, and interengaging means between the various logs and between the false ends and extending ends of the mortise logs to tie the structure together.

3. A building construction comprising superimposed layers of logs arranged in the form of an enclosure, some of the logs having mortises at each end the other logs having tenon ends, the mortise and tenon logs alternating with each other in the vertical direction as well as in each 75

layer, all of the logs having single longitudinal grooves in their crowns, and all of the logs, excepting the bottom layer, having a double grooving in their nether sides producing a tongue occupying the single grooves simultaneously with the occupancy of the double grooving by the crowns thereby forming a water check.

4. A building construction comprising a layer of sill logs arranged in the form of an enclosure, said logs having a deep recess forming a flashing, a foundation on which said logs are laid, the foundation going into the recess, layers of logs of which some have mortises adjacent to each end and the others having tenon ends to fit in the mortises superimposed upon said sill logs in wall formation, the crowns of all of the logs having single grooves, and the nether sides of all of the logs excepting the sill logs having a double grooving providing a channel occupied by the crowns and forming tongues occupying the single grooves.

5. A building construction comprising superimposed layers of logs arranged in the form of an enclosure, some of the logs having mortises

near each end to receive the tenon ends of the remaining logs and certain ones of the logs having mortises in vertical series on the interior of the construction, said mortise and tenon logs occurring in alternation in the vertical direction as well as in each log layer, means embodied in the logs at the places where they contact due to superimposition for keying them together and producing a water check, and a partition structure consisting of logs with similar keying means therebetween, the ends of said logs being set in the vertical series of mortises.

6. In a building construction, a unit of said construction comprising a log smooth-surfaced and uniformly cylindrical, said log having a longitudinal single groove in its surface and having a longitudinal double grooving on the opposite side producing a tongue diametrically opposite to said single groove, said log having at least one mortise equal in diameter to that of the log and of a depth that it communicates with said single groove.
